(57) **CLAIM**

The ornamental design for a modular shelf light as shown and described.

DESCRIPTION

FIG. 1 is a perspective view of a modular shelf light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the modular shelf light;

FIG. 10 is a perspective view of the modular shelf light in a first alternate configuration with only utilized attachments shown for clarity of illustration;

FIG. 11 is a perspective view of the modular shelf light in a second alternate configuration with only utilized attachments shown for clarity of illustration;

FIG. 12 is an enlarged view of portion 12 shown in FIG. 1; and,

FIG. 13 is an enlarged view of portion 13 shown in FIG. 1. The dot-dash broken lines represent boundaries of the enlarged portions and form no part of the claimed design.
